UNITED STATES PATENT OFFICE.

BENJAMIN VAN HOESEN, OF ULMER, TEXAS.

LOCK.

1,139,933.

Specification of Letters Patent. Patented May 18, 1915.

Application filed February 17, 1914. Serial No. 819,242.

To all whom it may concern:

Be it known that I, BENJAMIN VAN HOESEN, a citizen of the United States, residing at Ulmer, in the county of Grimes 5 and State of Texas, have invented certain new and useful Improvements in Locks, of which the following is a specification.

This invention relates to new and useful improvements in locks, and has particular reference to that type of locks in which there is provided a slideable bolt and means for so latching the bolt in its projected position that it cannot be operated from the outside without a key, the latching means being, however, movable out of engagement with the bolt so as to permit it to be readily operated by means of an ordinary door handle.

The primary object of my invention is to improve upon the construction illustrated and described in my prior Patent No. 1,052,105, of February 4, 1913, by providing means operated from the interior of the door for dead-locking the bolt in its projected position, thus preventing any retraction of the bolt, even by the use of a key, from the outside of the door.

A further object of the invention is to provide a rotatable barrel within which the key is insertible, and to provide a detent adapted to hold the barrel in a position where the key may be readily inserted.

A further object is to improve the details of construction of the lock shown in my aforesaid patent.

My invention is illustrated in the accompanying drawings, wherein:—

Figure 1 is a side elevation of a lock constructed in accordance with my invention, 40 the inside face-plate of the casing being removed. Fig. 2 is a like view to Fig. 1 but showing the dead-lock raised and the key in position to actuate the tumbler. Fig. 3 is a section on the line 3—3 of Fig. 1. Fig. 45 4 is a perspective detail view of the barrel, the tumbler, the latch for the tumbler and wards. Fig. 5 is a perspective view of the key whereby the lock is actuated.

Corresponding and like parts are referred 50 to in the following description and indicated in all the views of the accompanying drawings by the same reference characters.

Referring to these drawings, 2 designates the lock casing consisting of the two face 55 plates 3 and 4 and the surrounding rim 5 which includes the end-plate 6 formed with

an opening 7 through which the bolt 8 projects. The bolt 8 may be of any usual and desired form and is mounted between guides 9 and 10, the forward end of the bolt being 60 guided in the opening. The bolt is likewise guided upon a member 11 which forms the upper part of the keyward, as will be later described.

Rotatably mounted in the side plates 3 and 4 is a barrel 12 having a polygonal opening 13 for the passage of a knob-shank. This barrel has a projecting arm 14 which projects into a slot 15 formed in the upper face of the bolt. By rotating the barrel by 65 means of the knob, the bolt may be retracted against the force of a spring 16 supported in a slotted post 17.

For the purpose of holding the bolt in its projected position and preventing its retraction by means of the barrel 12, I provide a tumbler 18 which is movable vertically toward and from the bolt and is supported between the side plates 3 and 4 and immediately in front of the member 10. 70 This tumbler has the form of a vertically sliding block provided at its end adjacent the bolt 8 with a tooth 19 engaging in a recess 20 formed in the under face of the bolt. 75

The tumbler 18 has sliding engagement with the rear face of the base of the ward member 11 and is urged upward or into engagement with the notch of the recess 20 by means of a spring 22, whose rear end is supported in any suitable manner within the 80 casing. In order to permit the sliding tumbler 18 to be forced downward to release the bolt, I provide the tumbler with a pin 24 which projects out through a slot 25 in the side plate 4, upon the inside of the door. 85

In order to latch the tumbler 18 out of engagement with the bolt and thus permit the bolt to be operated by a key, I provide the spring-actuated sliding latch 26 disposed at right angles to the tumbler 18 and longitudinally shiftable into or out of engagement with the tumbler. This latch is formed at one end with a tooth 27 which engages in a recess 28 formed in the rear face of the tumbler. The latch 26 is supported 90 beneath the guide 10 and rests upon a guide 23. A spring acts to force the latch toward the tumbler 18 so that when the notch 28 is brought into registry with the tooth of the latch the latch will snap into engagement with the tumbler. The latch 26 is provided in both faces with the outwardly projecting studs 95 100 105 110

29 which extend out through slots 30 in the plates 3 and 4.

In order to provide means for preventing the door being unlocked even by means of a key, I provide within the casing 2, the vertically movable dead-lock 31 which has the form of a vertically slideable block disposed between guides 32 above the bolt, this block being formed with a tooth 33 adapted to engage in a notch 34 formed in the upper face of the bolt. This dead-lock 31 is provided with a pin 35 which projects out through a slot on the inside face plate of the lock casing and can only be operated from the inside. When the bolt is projected and this sliding block or latch 31 is forced downward into engagement with the bolt, it is obvious that the bolt cannot be retracted until the deadlock is raised. The frictional engagement between the guides 32 and the dead-lock 31 is such that the dead-lock will be held in a raised position or held in its lowered position against accidental movement. In this connection it will of course be understood that I may interpose a leaf-spring between the dead-lock and one of the guide members 32, for creating the necessary friction between the dead-lock and the other guide member, without departing in any way from the spirit of this invention.

For the purpose of permitting the key to be used for disengaging the tumbler 18 from the bolt, I provide the outer face-plate with an arcuate key-slot 36 which opens into a circular aperture within which is mounted the rotatable barrel 37. This barrel is slotted as at 38 to receive the bit of the key and the middle portion of the barrel is enlarged relatively to the end-portions thereof and is formed with a notch 39 adapted to be engaged at one point in the rotation of the barrel by the spring 40. This spring 40 is supported at one end in any suitable manner and adjacent its free end being bent to form a tooth engageable with said notch. The purpose of this spring 40 is to hold the barrel so set that its slot 38 is coincident with the slot 36 to permit the ready rotation of the key, this spring, however, not preventing the ready rotation of the barrel by means of the key. Between the barrel 37 and the tumbler 18 there is provided a ward member 11, previously referred to. This consists of a block having a relatively wide basal portion, the upper portion of the block being slotted to provide the upwardly extending ward 41. The key 42 as shown in Fig. 5, is flat and at its extremity is formed with the curved bit 43 which is slotted as at 44 producing a pair of spaced arcuate tongs. This slot receives the ward 41 when the key is turned to the position shown in Fig. 2. The face of the tumbler 18 adjacent the ward member 11 is formed with outwardly projecting pins 45 adapted to be engaged by

the bifurcated key-bit as the key is turned, as illustrated in Fig. 2. It will thus be seen that when a key of this character is inserted in the lock and then rotated, the ends of the bit tongs will engage the studs or pins 45 and a further rotation of the key will act to depress the tumbler 18 and carry the tooth 19 out of engagement with the notch 20, so as to permit the bolt to be shifted rearward by turning the knob.

The operation of my invention is as follows:—Under normal circumstances and when the door is not locked, the tumbler 18 is held out of engagement with the bolt 8 by means of the latch 26 and in this condition a rotation of the knob-shank will cause a rotation of the barrel 12, and this in turn will retract the bolt against the force of the spring 15. When it is desired to latch the bolt, however, the latch 26 is pushed backward so that the tooth 27 thereof escapes the notch 28 and the spring 22 then acts to force the tumbler upward and its tooth into engagement with the notch 20. The tumbler can only be retracted from the outside by means of the key, previously described. When the key is turned in a clockwise direction the tumbler 18 is depressed, and when it reaches a proper position the spring 30 forces the latch 26 into engagement with the notch 28, after which the bolt may be retracted by means of the barrel 12. Upon the inside of the door, however, the bolt may be released from its engagement with the tumbler by depressing the tumbler through the pin 24, thus carrying the tumbler down until the tooth on the latch 26 engages in the notch 28.

When it is desired to dead-latch the door from the inside to absolutely prevent the actuation of the tumbler by the key, the dead-lock 31 is shifted downward while the bolt is in its projected position and engages in the notch 34. Under these circumstances while the key can operate the tumbler, it will not release the bolt from the dead-latch 31. The bolt 8 is made reversible so as to be of use on either side of the door. To that end I duplicated the notch 20 and the notch 34 so as to provide a notch 20^a opposed to the notch 20 and a notch 34^a opposed to the notch 34. It will also be noted that the upper end of the ward 41 extends into a slot 8^a formed in the bolt 8, thus acting to guide the bolt and at the same time prevent any lateral deflection of the ward.

Having thus described the invention what is claimed as new is:—

1. In a lock of the character described, a casing including side-plates, a bolt within the casing, a tumbler engaging the bolt, a barrel rotatably mounted in the casing and having a longitudinally extending slit therein adapted to receive the shank of a key, the side wall of the casing being formed

- with a slot adapted to receive the bit of the key and to register with the slot in the barrel, and a spring having a detent portion engaging the barrel, the barrel being provided with a longitudinally extending notch engaged by said spring and so disposed that the spring yieldably holds the barrel with its slot in registration with the slot in the side wall of the casing.
- 5 2. In a lock of the character described, a casing including side walls, one of the side walls being formed with a slot to receive the bit of a key, a longitudinally movable bolt mounted in the casing, a vertically movable tumbler disposed in the casing and shiftable into or out of engagement with the bolt to lock it in a projected position, a spring normally urging the tumbler into engagement with the bolt, a ward disposed between said 10 tumbler and the slot in the wall of the casing, a rotatable barrel having reduced ends
- 15
- 20

mounted in the walls of the casing, said barrel having a longitudinal slot adapted to register with the slot in said casing wall, the barrel also being provided with a longitudinally extending notch, and a resilient 25 detent yieldably engaging said notch.

3. In a lock of the character described, a casing, a slideable lock bolt having a longitudinally extending recess formed in its 30 under face, a vertically movable tumbler engageable with the bolt, and a ward member disposed in advance of the tumbler, the upper edge of the said ward member being disposed in the recess of the bolt and constituting a guide therefor.

In testimony whereof I affix my signature in presence of two witnesses.

BENJAMIN VAN HOESEN. [L. S.]
